 METHOD AND APPARATUS FOR DESCRIBING
CIRCULAR ARCS

Attilio R. Spicacci, Germantown Manor, Greene and
Horster Sts., Philadelphia 19, Pa.
Filed Mar. 28, 1960, Ser. No. 18,112

2 Claims. (Cl. 33—27)

This invention relates generally to a novel method and apparatus for describing circular arcs.

As is well known to those versed in the art of mechanical drawing, it is often necessary to describe arcs of relatively large radii beyond the range of ordinary drawing compasses. It has heretofore been necessary in drawing arcs of relatively great radii to employ a beam compass. However, the beam compass, when employed to draw arcs of large radii, is quite cumbersome, unwieldy, and otherwise difficult to use. Moreover, when the centerpoint of the arc is inaccessible, the beam compass cannot be used, and approximations or tedious expediences must be employed.

Accordingly, it is an object of the present invention to overcome the difficulties mentioned above in describing arcs of large radii, and to provide a method and apparatus which enables one to quickly, easily, and accurately describe an arc of any desired radius, no matter how large, and wherein one practicing the invention operates entirely in the region of the arc being described.

It is another object of the present invention to provide a method and apparatus having the advantageous characteristics mentioned in the preceding paragraph, which is extremely versatile so as to be capable of solving practically all geometric-construction problems that can be done with a conventional compass, and with equal or improved facility.

It is a further object of the present invention to provide a drawing instrument of the type described which is extremely simple in construction and use, so as to be durable and reliable throughout a long useful life, and which can be economically manufactured for sale at a reasonable price.

Other objects of the present invention will become apparent upon reading the following specification and referring to the accompanying drawings, which form a material part of this disclosure.

The invention accordingly consists in the features of construction, and combinations and arrangements of elements and method steps, which will be exemplified in the following description, and of which the scope will be indicated by the appended claims.

In the drawings:

FIGURE 1 is a plan view showing a body part or trammel of the apparatus of the present invention;

FIGURE 2 is a sectional view taken substantially along the line 2—2 of FIGURE 1, and illustrating a marking device in association therewith;

FIGURE 3 is a partial sectional view taken substantially along the line 3—3 of FIGURE 1;

FIGURE 4 is an enlarged fragmentary plan view of the body part of FIGURE 1;

FIGURE 5 is a plan view of another part, or abutment member of the instant apparatus;

FIGURE 6 is a sectional view taken substantially along the line 6—6 of FIGURE 5;

FIGURE 7 is a plan view showing the body part or trammel and abutment members in operative relation with each other; and

FIGURE 8 is a diagrammatic illustration of the geometrical principles involved in the instant invention.

Referring now more particularly to the drawings, and especially to FIGURES 1—4 thereof, a generally flat body part or trammel is generally designated 10, and is advantageously formed of relatively stiff, flat, transparent

2

material, such as plastic or the like. The body part or trammel 10 includes a pair of outwardly, generally oppositely extending legs 11. The legs 11 are arranged symmetrically about the center line of the body part 10, as the line 2—2. Thus, the legs 11 of body part 10 are substantially coplanar, and are formed on one side, the lower side as seen in FIGURE 1, with straight edges 12 which define therebetween a reentrant or included angle α having its vertex on the center line 2—2. The angle α is of less than 180°; and, the line 2—2 defines the bisector of the angle. The straight edges 12 terminate short of their juncture or vertex and are arcuately cut out, as at 13 adjacent to but spaced from the center line 2—2. Intermediate the arcuate cutouts 13, the body part 10 is provided with a projecting portion or extension 14, which extends along the center line 2—2 into the space within the angle α . Formed in the extension 14 is a through opening or hole 15, which may be of tapering or conical configuration to facilitate engagement therethrough of a marking device or stylus. The opening or hole 15 is located on the center line or bisector 2—2 of the angle α and within the angle, being spaced from the straight edges 12 or their extensions a predetermined distance. Of course, the spacing of the hole 15 from the edges 12 or their extensions is the distance or length of a line normal to the edges or their extensions. It should also be noted that the hole 15 is located within the triangle bounded by the edges 12 and a line extending between the distal ends of the edges.

30 The legs 11 of the body part 10 terminate at their outer ends in knife edges 16, which edges extend in parallelism with each other and with the bisector line 2—2. In addition, there may be provided adjacent to one or both edges 16 a suitable marking or line 17 extending normal to and terminating at the respective edge 16. The markings 17 are located so that a line through the markings is normal to the center line or bisector 2—2. The stylus-receiving hole 15 is also located on a line between the markings 17.

35 Also provided on the body part, extending outwardly directly opposite to the extension 14, is an extension 19. The extension 19, which extends upward in FIGURE 1 along the center line or bisector 2—2, terminates at its upper or outer end in a knife edge 20 extending normal to and intersecting with the center line. Provided on the extension 19 is a marking 21 coincident with the center line or bisector 2—2 and which may be a line extending normal to the edge 20.

40 In addition to the body part 10, there are provided a pair of disc elements or abutment members 23, one being shown in FIGURES 5 and 6. Each abutment member includes a generally flat, preferably transparent circular body or disc 24, advantageously fabricated of plastic, and provided with markings in the nature of intersecting 45 lines or cross hairs 25 which intersect at the center of the circular body. A pair of pins 26 are embedded in the body 24 of the disc element 23, eccentrically thereof, with their points projecting downward beneath the underside of the body for impaling in a drawing board or 55 similar supporting surface.

50 As seen in FIGURE 7, a pair of disc members 23 are provided. It should also be noted that each of the disc members is of a radius equal to the distance, as discussed hereinbefore, between the hole 15 and each of the straight edges 12 or an extension thereof normal thereto.

55 The principles and procedures of operation may be understood by reference to FIGURES 7 and 8.

The angle included between the straight edges 12 of the 60 body 10, hereinbefore designated α , bears a relationship to the length of the chord 30 between the points 31 and 32, such that the function $2 \sin \alpha$ is equal to the ratio of

the length of chord 30 to R. Therefore, the length of chord or line 30 between points 31 and 32 equals $R \times 2 \sin \alpha$.

After drawing the line or chord 30, one of the abutment members or discs 23 is placed at each end of the chord with the intersection of its cross hairs 25 directly over the adjacent point 31, 32. In this location, the pins or prongs 26 of each disc member 23 are impaled in the supporting surface to anchor the disc members in position.

The body part 10 is then placed flat on the supporting surface and its straight edges 12 brought into respective engagement with the circular or cylindrical peripheral edges of respective disc members 23, the condition shown in FIGURE 7. A marking device, stylus, or pencil, as at 36 in FIGURE 2, is inserted through the hole 15 to engage the supporting surface, and the body part or trammel 10 in the condition of FIGURE 7 is moved with the edges 12 in sliding engagement with the respective discs 23. Thus, the extension 14 and its received marking device move between the disc members 23, and the arc 33 is thereby marked or traced on the supporting surface. The traced arc 33 will be circular and of the radius R having the hereinbefore-mentioned mathematical relationship to the angle α and the length of chord 30.

This may be mathematically demonstrated (without rigor) in the following manner:

(1) In plane geometry, if the sides of a constant angle move through fixed points, the locus of the vertex of the angle is a circular arc; and

(2) A chord of such arc through the mentioned fixed points has a length equal to the radius of the arc times twice the sine of the constant angle.

In the diagram of FIGURE 8, the sides 38 of the angle α respectively pass through fixed points 39, and upon movement of the sides 38 through their respective fixed points 39 while maintaining the angle constant the locus of points defined by the vertex 40 is a circular arc 41 having a radius R and a chord 42 extending between the points 39.

The ratio, chord 42:radius $R = 2 \sin \alpha$.

Referring again to FIGURE 7, as the hole 15 of extension 14 is spaced from the extensions of straight edges 12 a distance equal to the radius of each disc member 23, a straight line between each point 31, 32 and the hole 15 is always parallel to the adjacent straight edge 12 throughout the sliding motion of the body part 10. Therefore, an angle defined between the points 31, 15, and 32 is constant and equal to the angle α between the edges 12 throughout the sliding operation of the body part 10.

If, for example, it is desired to determine the radius of arc 33, and the angle α is known to be $172^\circ 49' 10''$, the fixed ratio between the chord 30 and radius R of the arc equals $\frac{1}{4}$. While a single body part 10 of one predetermined angle α is capable of use over a wide range of conditions, it may be desirable to provide a set of such body parts having different fixed angles α for different chord-to-radius ratios.

If it is desired to draw a tangent at any point to the arc 33, say at the point 34, it is only necessary to mark the locations of lines 17, at opposite ends of the legs 11, and then draw a tangent, as at 45 through the lines 17 and point 34. Also, a normal to the arc 33 may be provided at any desired point, say point 34, by drawing a line through the latter point and through the marking line 21 of the extension 19, such a line being indicated at 46.

While certain operations employing the instant device and method have been described hereinbefore, it is apparent that many additional operations may also be performed. For example, the following geometrical constructions may be easily executed employing the method and apparatus of the instant invention:

(1) Extending an arc on either end;

(2) Having a given arc, to describe another arc of another radius tangent to the given arc at a given point;

(3) To describe an arc of a given radius through two given points;

- 4
- 5 (4) To determine the radius of a given arc;
(5) To describe a circular arc through three given points; and
(6) To describe an arc concentric with and at a given distance from a given arc.

It will now be understood that the method and apparatus of the instant invention is capable of performing a wide variety of geometrical constructions, wherein it is entirely unnecessary to use the center of an arc, and wherein the entire operation is performed in the region of the arc to be described without regard to the length of the radius of the arc.

In describing an arc according to the method of the present invention, the method may be considered as involving the following procedure:

- 10 (1) Providing a constant angle having a fixed relation to the ratio of a chord to the radius of any circular arc;
(2) Laying out a chord of a length determined by the particular ratio;
(3) Fixing the abutment members at the ends of the laid-out chord; and
(4) Sliding the fixed angle along the abutment members to describe an arc defined by the locus of the angle vertex.

The device and method are capable of extremely accurate results, as high accuracy may be built into the body part, and there are no moving parts, as would require manufacturing tolerances and impair accuracy.

From the foregoing, it will now be appreciated that the present invention provides a method and apparatus for describing circular arcs and accomplishing related geometrical constructions, which fully accomplish their intended objects and are well adapted to meet practical conditions of manufacture and use.

Although the present invention has been described in some detail by way of illustration and example for purposes of clarity of understanding, it is understood that certain changes and modifications may be made within the spirit of the invention and scope of the appended claims.

For example, it is appreciated that the stylus receiver or opening 15 may be located approximately at the vertex of the angle α , and that the abutment members 23 may then be slender pins or the like of minute radius. While such variation is not preferred for accurate work, it might be satisfactory for certain purposes, and of course is contemplated as embraced within the instant invention.

What is claimed is:

1. A drawing instrument comprising a generally flat unitary body having a pair of fixed straight edges defining therebetween an angle of less than 180° and adapted to rest on a supporting surface with said edges in a plane parallel to said supporting surface, an extension on said body at the juncture of said straight edges for locating a tracing point on the bisector of said angle at a predetermined distance from said straight edges, and a pair of abutment members each having its radius equal to said predetermined distance and adapted to be selectively positioned on a supporting surface, whereby said tracer point is adapted to describe an arc between the centers of said discs upon sliding movement of said straight edges along said discs, said body being provided at opposite edges thereof with a pair of fixed tangent markings in alignment with each other through the location of said tracer point for locating a tangent to said arc, and said body having an additional edge provided with a fixed normal marking coincident with the bisector of said angle extended externally of said angle.

2. A drawing instrument comprising an integral body having a pair of straight edges defining therebetween a fixed angle and adapted to rest on a supporting surface with said straight edges in a plane parallel to said supporting surface, an extension on said body at the juncture of said straight edges for locating a tracing point on the bisector of said angle at a predetermined distance from

said straight edges, and a pair of disc members each having its radius equal to said distance and adapted to be selectively positioned on a supporting surface, whereby said tracer point is adapted to describe an arc between centers of said disc members upon sliding movement of the said straight edges along said disc members, said disc members each being provided with a central marking for accurate location over a point on said surface, said body being generally flat and having a second pair of straight edges parallel to each other and to the bisector of said angle, there being markings on said second pair of straight edges in alignment with each other through the location of said tracer point, and said body being formed with an

additional straight edge extending normal to and intersecting with the bisector of said angle extended externally of said angle, said additional straight edge being provided with a marking in alignment with the external extension of said angle bisector.
